Primary Examiner — Jonathan J Han*Assistant Examiner* — Molly K. Orzechowski(74) *Attorney, Agent, or Firm* — Bold IP PLLC;
Christopher Mayle(57) **CLAIM**

The ornamental design for a shoe insert, as shown and described.

DESCRIPTION

FIG. 1 is a side perspective view of a shoe insert in accordance with the present invention;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a bottom view thereof.
